CLAW GRABHOOK

Woodard Spann, Gunnison, Colo.

Application February 10, 1947, Serial No. 727,572

6 Claims. (Cl. 294—107)

1

This invention comprises novel and useful improvements of a claw grab hook, and more specifically pertains to a novel construction and operating means for a grab hook of the type employed for moving hay or other bulky substances.

The principal objects of this invention reside in providing a novel construction of a grab hook; in providing improved operating means therefor; in providing, as a component part of the operating means, a construction operable to positively and securely sink a hook into a mass of material to be lifted thereby; in providing an operating mechanism selectively operable to open and close the jaws of the hook, lift the same and cause the jaws to release their load as desired; and withal to provide a device which is extremely simple in construction, durable and dependable in operation, readily constructed of widely available, inexpensive materials and which is highly efficacious for the purposes intended.

These, together with various ancillary objects of the invention which will later become apparent as the following description proceeds, are attained by this device, one embodiment of which has been illustrated by way of example only in the accompanying drawings, wherein:

Figure 1 is a top plan view of the claw grab hook;

Figure 2 is a side elevational view of the grab hook, shown in the open position in full lines and in closed position by the dotted lines;

Figure 3 is a side elevational view of the grab hook;

Figure 4 is a detail view in transverse vertical section through one of the hook jaws, taken substantially upon the section line 4—4 of Figure 1;

Figure 5 is a fragmentary horizontal sectional view showing the hinged connection of the hook, taken substantially upon the section line 5—5 of Figure 2; and

Figure 6 is an enlarged fragmentary detail view taken in vertical section through one of the jaw operating means.

Referring now more specifically to the accompanying drawings, wherein like numerals indicate similar parts throughout the various views, 10 designates a support bar which is shown attached as by a hook and eye connection to a hook lifting means 12 which may suitably be formed of a cable attached to a winch or other operating means, whether carried by a tractor or by a supporting frame, not shown. At its lower end, the support bar which may be conveniently formed of

2

rectangular cross section, as indicated in Figure 1, is connected, as by a single pivot pin 14, with the outer terminal of members 16 whose other extremities are rigidly connected to the tops of rectangular jaw frame members 18. As will be noted by reference to Figures 1 and 4, the members 16 are preferably formed of angle iron or the like, and the jaw frame members 18 are similarly formed and are rigidly connected in any suitable manner to the support members 16.

It will thus be seen that the jaw members are generally triangular in shape, with the sides of the triangles consisting of a pair of angle iron support members 16, and the base of the triangle being formed by one side of the triangular jaw frame member 18, the triangular jaw members being pivoted at their apices to the lower end of the support rod or bar 10 at the lower end thereof by the single pivot pin 14. The arrangement is such that when the weight of the jaws and their contents is supported by the cable 12 and support bar 10, the jaws will pivot downwardly to the dotted line position shown in Figure 2; the teeth or tines 20 depending downwardly therefrom being enmeshed in the mass of material with which the jaws are engaged.

As shown more clearly in Figure 4, each jaw is provided with two rows of teeth; although it will be evident that this number may be varied, as desired, to suit the exigencies of particular environments and situations. The teeth are preferably of a resilient or spring nature, and for this purpose may each consist of a single piece of spring wire or flat spring steel, or with a loop or bight portion 22 intermediate their ends, which bight portion constitutes a coil spring to give resiliency to the tooth. The downwardly extending extremity of each tooth may be curved slightly toward the other jaw, while the other extremity may extend laterally through the angle iron frame member of the jaw frame 18, and be adjustably attached thereto as by threaded engagement and fastening nuts 24.

Attention is now directed more specifically to Figures 2 and 6 for an understanding of the jaw operating means. A cross frame 26, indicated generally in Figure 2, is composed of a pair of parallel angle iron or cross bars 28, suitably attached to the support bar pin and journalling between their opposite extremities a pair of pulleys. Preferably the cross frame is rigidly attached to the support bar pin, although it may be pivoted thereto as desired, and the parallel members 28 forming a part of the cross frame are rigidly se-

cured to each other, as by the trunnions for the pulleys 30.

Carried by and rising from the mid point of the innermost of the members 18, and upon the upper surface thereof, are a pair of guide rods 32 attached to the frame members, as by a screw-threaded connection and nut 34. A weight 36 of considerable bulk, and preferably in the form of a tubular sleeve member is loosely and slidably disposed for movement upon the rod 32, but having its upward travel thereon limited, as by an adjustable nut 38, is attached as by an eye 40, with an end 42 which constitutes one of a pair of split or bifurcated ends of a jaw-operating cable means 44. As shown in Figure 2, the ends 42 are entrained over the pulleys 30 where they are guided, extend downwardly between the parallel members 28 of the cross frame and have their lower ends attached to the weights 36.

The operation of the device is as follows. When it is desired to grasp a load of material with the hook, the lifting cable 12 is released, and the hook is supported solely from the jaw-operating cable 44. When in this position, the weight of the jaw assembly will be supported by the bifurcated cable members 42, and the weights 36 which will be at the upper end of their guide rods in engagement with the nuts 38, whereby the weights will support the jaws through the guide rods 32, the jaws being in their widely open position, as shown in full lines in Figure 2. The jaws are lowered, in their widely open position, until they contact with and rest upon the mass of material to be engaged. As the jaw-operating cable 44 is still further lowered, the weights 36 will slide down the guide rods 32 until they rest upon the jaw frame members 18 in the positions shown in Figures 2 and 6. It will now be apparent that if further penetration of the jaw teeth 20 into the mass of the material is desired, the cable 44 may be raised slightly and lowered, thus causing the weights 36 to rise and fall and produce a hammering effect upon the upper surfaces of the jaws which will serve to drive and embed the teeth 20 into the mass of material. It is preferably intended that the teeth shall generally assume the position shown in dotted lines in Figure 2. Now the jaw-operating cable 44 is released and the lifting means 12 is employed. As the bar 10 is raised, the entire weight of the jaws tends to swing the latter downwardly about their common pivot point 14, whereby the weight of the jaws, and the weight of the material impaled by the teeth 20 serve to further bias the jaws toward each other to firmly grip and retain the mass of material therebetween. As long as the entire load is suspended by the lifting cable from the common pivot point of the jaws, the latter will remain locked. When now the jaws and their load have been moved to the desired position, and it is intended to release the jaws, the jaw-operating cable 44 is placed under tension, and the cable 12 is slackened, whereby the weight of the contents urges the jaws to a fully open position, thereby releasing the load entrapped therebetween.

From the foregoing, it will be apparent that there has been provided a device by which the claws of the hook may be caused to close or release, by which the hook may be raised or lowered, and by which the jaws may be caused to penetrate a mass of material to completely engage the same, from a single set of controls and by a single operator of the device.

It is not intended to limit the invention to the exact construction shown and described in the drawings and specification, but all suitable modi-

fications may be resorted to falling within the scope of the appended claims.

What is claimed as new is as follows:

1. In combination, a pair of jaws, a support bar pivoted to said jaws and attached to a lifting means, a cross frame carried by said support bar, a jaw-operating means associated with said cross frame and connected with a lost motion connection to said jaws, said cross frame having arms overhanging said jaws, guide means on said arms for receiving said jaw-operating means, a guide carried by each jaw, a weight slidably engaging each guide for limited movement thereon, said jaw-operating means being connected to said weights.

2. In combination, a pair of jaws, a support bar pivoted to said jaws and attached to a lifting means, a cross frame carried by said support bar, a jaw-operating means associated with said cross frame and connected with a lost motion connection to said jaws, said cross frame having arms overhanging said jaws, guide means on said arms for receiving said jaw-operating means, a guide carried by each jaw, a weight slidably engaging each guide for limited movement thereon, said jaw-operating means being connected to said weights, said guide comprising a rod, said weight comprising a sleeve slidable on said rod and means on said rod limiting the movement of said weight.

3. In combination, a pair of jaws, a support bar pivoted to said jaws and attached to a lifting means, a cross frame carried by said support bar, a jaw operating means associated with said cross frame and connected with a lost motion connection to said jaws, guides extending from each jaw, means slidably mounted for limited travel on said guides and actuated by said jaw operating means for raising and lowering the jaws in an extended open position.

4. In combination, a pair of jaws, a support bar pivoted to said jaws by a common pivot at one end and attached to a lifting means at the other end, a cross frame carried by said support bar, a jaw operating means controlled by said cross frame and connected to said jaws, guides extending from each jaw, means slidably mounted on said guides and actuated by said jaw operating means for raising and lowering the jaws in an extended horizontal position, and stop means on said guides for limiting the movement of said first-mentioned means.

5. In combination, a pair of jaws, a support bar pivoted to said jaws by a common pivot at one end and attached to a lifting means at the other end, a cross frame carried by said support bar, a jaw operating means controlled by said cross frame and connected to said jaws, guides extending from each jaw, means slidably mounted on said guides and actuated by said operating means for imparting a driving force to said jaws.

6. In combination, a pair of jaws, a support bar attached to said jaws at one end and to a lifting means at the other end, a cross frame carried by said support bar, a jaw operating means controlled by said cross frame and connected to said jaws, guides extending from each jaw, weights slidably mounted on said guides and actuated by said operating means for selectively raising and lowering the jaws in a substantially horizontal position, stop means on said guides for limiting the movement of said weights, and means commonly secured to said jaws and support bar for effecting simultaneous closing move-

ment of the jaws responsive to a predetermined placement of said weights on the guides.
